UNITED STATES PATENT OFFICE.

EDWARD J. FINK, OF BRONX, NEW YORK.

ORNAMENTAL BODY.

Application filed September 12, 1925. Serial No. 56,097.

This invention relates generally to the manufacture of gems known as "cabochons" and more particularly to the application thereof for various purposes.

5 The subject matter of this invention is closely related to the invention described in my co-pending application Ser. No. 56,098, filed Sept. 12, 1925.

For a full understanding of the invention 10 and characteristic features thereof, reference is made to the accompanying drawings in which—

Fig. 1 is a plan view of a plate carrying a plurality of cabochons arranged singly and 15 in groups;

Fig. 2 is an elevation of a part thereof, partly in section;

Figs. 3 and 4 are side elevation and end view, respectively, of a portion of the plate 20 carrying a group of cabochons, as severed from the plate and mounted on a pin;

Fig. 5 is a plan view of another portion of a plate carrying another group of cabochons, severed from the plate; and

25 Fig. 6 is a plan view of a modification of the form shown in Fig. 5.

This invention is based on the discovery more fully described in my said co-pending application, that when a body, as for 30 instance a plate, having a perforation is pressed upon a body of molten vitreous material, the upper surface of the material assumes a definite curvature. Thus when the perforation is circular, the upper surface is spherical. The curved cabochon surface is so uniformly smooth that even the best and most careful polish could not improve it.

Since a natural polish is thus obtained as 40 the result of the process of producing the cabochons, the latter may be formed and mounted by one and the same operation. Advantage may be taken of this unique feature in many ways and for numerous 45 purposes.

I therefore wish to emphasize that the drawings are intended merely as generally illustrative and suggestive of the almost unlimited scope of application of the invention.

50 In Figs. 1 and 2 I have shown a plate 1 of relatively small thickness and generally of the order of stock used for mounting gems and precious stones. This plate, which may be called a stencil plate is shown as 55 perforated and carrying 4 groups *a*, *b*, *c*, and *d* of cabochon gems. Group *a* represents a

plurality of typical cabochons 10. Group *b* represents a plurality of oval cabochons 11. Group *c* indicates a group composed of a plurality of different sized cabochons 12, 60 13 and 14 representing an ornamental unit. Group *d* indicates a relatively large number of cabochons 15 defining the letter A.

The common characteristic feature is a slight bevel or flaring 2 of the perforations 65 at the lower side of the plate and preferably also a similar flaring 3 at the upper end of the perforations. When molten glass, or vitreous material in general, is pressed through the perforations as for instance by 70 pressing the plate 1 upon a body of molten glass, the glass as it issues from the perforations expands slightly and thus after cooling cannot be removed in a downward direction. At the same time the molten glass 75 fills the flaring portion 2 so that after cooling a secure anchor is also provided against motion in the other direction. After the cabochons have been formed, the excess glass at the bottom is removed as by grinding and 80 then the single gems, groups or units are cut from the plate with enough of the metal to provide a mounting.

Thus, as indicated, group *c* is shown as cut out from the plate in the form of a disk 4 85 and then mounted upon a pin 5 forming a stick pin. As indicated in Fig. 5, group *d* may be cut out to serve as an ornamental symbol.

As indicated in Fig. 6, the letter A may be 90 formed by long cabochons instead of a group of circular forms. The elongated perforations 6 act the same as other perforations. The cabochons produced thereby are uniformly rounded and form in substance semi-cylinders with the exception that the ends are also rounded.

The form of the gem depends generally on the outline of the perforation. The curvature of the upper surface adapts itself to the 100 different conditions.

In the foregoing I have restricted myself to the illustration of groups formed by a single perforation or by a plurality of perforations grouped together to produce either single 105 gems or pluralities of individual gems grouped together. While the number of combinations that may thus be produced is practically infinite, I am by no means limited thereto. The form of the upper surface may be modified by various ways. A 110 group of perforations may be so correlated as

to size and spacing from each other that the upper surface is a unitary composite surface of any desired plan and profile. When perforations are so close to each other that the 5 molten material issuing at the top coalesces or flows together, a single surface is produced exhibiting to a greater or lesser degree the characteristics of the individual forms as they would be produced separately from each 10 other, but these forms are modified more or less by the degree of coalescence permitted. One illustration of this is the form shown in Fig. 6. The elongated perforations are in effect a large number of circular perforations 15 in juxtaposition and so overlapping each other as to form two straight side walls. If the overlapping were such as to produce scalloped side walls, the cabochon produced would include a plurality of mainly spherical 20 bodies interconnected by webs the width and heights of which is a function of the degree of overlap. There is, in fact, no limit in respect to the formation of modified cabochon bodies. There is not a geometrical configuration 25 that may not be simulated. Flowers and animals may be imitated more or less ornamenteally depending on the skill and experience of the designing artist. It would be futile within the scope of this specification 30 to even attempt to give illustrations of the various forms that may be created by the method described.

It is needless to say that the plate need not be plane or that the flaring of the openings 35 need not be produced by beveling or counter-boring. The perforations may be produced by punching dies or in fact in any well known manner. The recesses for producing the anchoring effect may be provided by 40 bending, indenting, pressing the plate or stock upon which the mounting is to take place.

Aside from the general utility of the invention in respect to the production of gems 45 and ornamental designs proper, as above referred to, there is another field of application which I consider of great importance. The invention is particularly applicable to the formation of signs of all descriptions. 50 Thus any name, word or phrase may be composed of cabochons, as suggested in Fig. 5. The cabochons may be of any color or of different colors. In the day time, the signs are visible by light reflections, while provisions 55 may be made to make them conspicuously visible, at night by transmission of

light through them. The art of illumination is widely understood and appreciated and has proceeded to such degrees of specialized skill bordering almost on the realm of magic, 60 that it would be superfluous to particularly indicate some of the many devious ways by which the artistic effect of signs made in accordance with my invention may be conspicuously brought out. 65

Also in this respect there is no limit to the combinations of words, signs, symbols and emblems that may be produced as the result of creative imagination.

I claim:

1. An ornamental structure of the character described, comprising a plate having substantially plane surfaces and an opening extending from one plane surface to the other, and a body of vitreous material in said opening, having portions preventing removal of the body in either direction, one end portion presenting a symmetrically rounded surface having the characteristics of a highly polished cabochon surface. 70

2. An ornamental structure of the character described, comprising a plate having substantially plane surfaces and an opening extending from one plane surface to the other, the opening having a lateral enlargement of 85 smaller axial extent than the thickness of the plate, and a body of vitreous material in said opening having a laterally enlarged portion corresponding to and filling the enlarged part of the opening, one end portion of the 90 said body presenting a symmetrically rounded surface having the characteristics of a highly polished cabochon surface.

3. An ornamental structure of the character described, comprising a plate having substantially plane surfaces and an opening extending from one plane surface to the other, the opening having an enlargement adjacent to one surface, and a body of vitreous material in said opening, having at one end an 100 enlargement corresponding to and filling the enlargement of the said opening and having at its opposite end a portion presenting a symmetrically rounded surface having the characteristics of a highly polished cabochon surface, the said portion projecting 105 beyond the surface of the plate and having a width greater than the width of the opening.

In testimony whereof I affix my signature.

EDWARD J. FINK.
